HEEL LIFT CEMENTING AND ASSEMBLING MACHINE

Original Filed Dec. 7, 1914 4 Sheets-Sheet 4

UNITED STATES PATENT OFFICE.

ERVIN L. PAGE, OF GEORGETOWN, MASSACHUSETTS, ASSIGNOR TO PAGE MACHINE CO., INC., OF HAVERHILL, MASSACHUSETTS, A CORPORATION OF MASSACHUSETTS.

HEEL-LIFT CEMENTING AND ASSEMBLING MACHINE.

Application filed December 7, 1914, Serial No. 875,844. Renewed July 20, 1923.

To all whom it may concern:

Be it known that I, ERVIN L. PAGE, a citizen of the United States, residing at Georgetown, in the county of Essex and State of Massachusetts, have invented an Improvement in Heel-Lift Cementing and Assembling Machines, of which the following is a specification.

This invention relates to certain improvements in heel-making machines and more particularly to certain improvements in heel-lift-cementing and assembling devices which are especially adapted for use in connection with a machine of the type shown in my Patent No. 1,223,728, in which a series of heel-holders, on which the assembled lifts may be placed, are flexibly connected to form an endless carrier, each holder being provided with heel-clamping means, so that, when the cemented lifts are assembled on the holder, they may be immediately clamped together and held in this position until the cement sets.

In another application, filed by me on July 8, 1914, Serial #849,836, which matured into Patent No. 1,320,410 on Nov. 4, 1919, I have described an improved means for simultaneously cementing and delivering the lifts necessary to form a heel, so that they may be conveniently picked up and placed in a heel form on the heel holder, and the object of the present invention is to provide improved means for performing, not only the functions of the cementing and delivering device above referred to, but to provide an apparatus which will, in addition collect the cemented lifts in a pile and deliver them in heel form on the heel holders of the carrier, as said holders are successively moved to a predetermined lift-receiving position, and which will also hold them in heel form on the holder while they are automatically clamped thereon.

I accomplish these objects by providing, in connection with a series of lift-holding compartments, as described in said prior application 849,836, a series of lift-supports, which are arranged in a line approximately parallel to the line of said compartments, and adjacent thereto and onto which a separating device is arranged to deliver the lifts, so that they may be moved to collect the lifts in heel form, and to deliver them onto the holder of the carrier. For a more

complete understanding of my invention reference is made to the accompanying drawing, in which,

Fig. 1 is a side elevation of a heel-making machine embodying my invention.

Fig. 2 is a detail view of the heel-clamping mechanism.

Figs. 3 and 4 are detail views of a lift-straightening device which I employ.

Fig. 5 is a sectional view, taken at the line *x*—*x* of Fig. 1, on a somewhat enlarged scale.

Fig. 6 is a section view on the line *y*—*y* of Fig. 5, some of the parts being broken away.

Fig. 7 is a plan view of the portion of the machine shown in Fig. 6.

Fig. 8 is a sectional view on an enlarged scale taken at the line *z*—*z* of Fig. 6.

Fig. 9 is a similar view showing the parts in a different position.

Fig. 10 is a detail sectional view of a portion of the cementing mechanism, taken at the line *w*—*w* of Fig. 5.

Fig. 11 is a detail view of one of the lift-assembling plates.

Fig. 12 is a sectional view at the line *v*—*v* of Fig. 7.

Fig. 13 is a view similar to Fig. 5, showing the parts in a different position.

Fig. 14 is a detail plan view of the lift-holding and collecting mechanism.

Fig. 15 is a detail sectional view of the lift-delivering mechanism.

Figs. 16 and 17 are detail sectional views of the lift collecting mechanism.

Figs. 18 and 19 are detail views of portions of the automatic clutch-operating mechanism.

As shown in the drawing, the frame 2 of the machine has an endless carrier mounted to move in an endless track therein, said carrier comprising a series of flexibly connected heel-holders 4, and being adapted to be intermittently driven from the shaft 8, by means of the main shaft 7 acting through a clutch mechanism which causes the shaft 8 to make one rotation and then stop, each time the treadle 9 is depressed, mechanism being provided between the carrier and said shaft 8, whereby the carrier is advanced the length of one holder each time the shaft 8 makes a complete rotation.

Each holder 4 is provided with a lift-

clamping means, which comprises a lift-engaging plate 10, carried by a rod 12, vertically mounted in the holder and in a breast gage 11, which projects thereon, and longitudinally movable therein, a spring 13 being arranged between the under side of the holder and an arm on said rod, to draw said rod inwardly and, therefore, the plate 10 towards the outer side of the holder 4.

10 Each rod 12 is provided with a roll 14, which is adapted to engage a rib 15 on the frame and to be raised out of clamping position thereby as the particular holder, on which it is mounted, approaches the heel-receiving position, as explained in the prior applications above referred to.

15

For reasons which will appear, an extension 16 of the rib 15 is provided directly beneath the lift-receiving position of the holders, said extension being pivoted to the end of said rib and being normally supported by a vertically movable support 17 having a tooth at one side which is arranged to be engaged by a dog 18 to lock the rod 20 against downward movement. A spring 20 is arranged beneath the end of the rod 17, which is of sufficient strength to support the section 16 in a horizontal position, and a spring 21 normally holds the dog 18 in engagement with the rod 17.

A table 25 is mounted at the front side of the machine near its left end, and extends approximately at right angles thereto, and a heel-lift holder 27 is mounted on said table and is provided with a series of vertically disposed compartments 28, each of which is adapted to hold a stack of lifts therein, said compartments being arranged in a row which extends approximately at 35 right angles to the carrier, or the direction in which the carrier is driven, and said compartments being, in practice, of sufficient number to contain all the different standard sizes of lifts which will, ordinarily, be used 40 in the construction of a heel. Said compartments are arranged in the order of their size, the largest being next the machine, and, when two or more lifts of the same size are required in a heel, the corresponding 45 compartments are made the same size.

The table 25 extends beneath the lower ends of the compartments 28, and has lift-supporting faces 25' directly beneath said compartments on which the bottom lift of each stack rests, said faces being arranged in horizontal planes at different elevations, each varying in elevation from the next adjacent face by the thickness of the lifts to be employed (see Fig. 12), the face next adjacent the carrier being at the lowest elevation and the others being at increasingly higher elevations relative thereto.

A lift-separator 30 is provided, composed of a series of lift-engaging portions, which are arranged correspondingly to said faces

25' and rest flat thereon, each portion being of a thickness slightly less than the thickness of the lifts. Said separator is slidably mounted in guideways 31 on the table 25, so that it may slide directly over the faces 25' and engage the lifts which may be supported on said faces and push them from beneath the stacks, spaces between the lower ends of the sides of the lift-holder 27 and the table 25 being formed, to permit the separator and the lifts to pass therebeneath, as shown in Fig. 15. The front end of each separator portion is provided with a recess 30' which is shaped to receive one side half of, or to fit against the side edge portion 60 of the particular heel-lifts which are to be placed in the compartment under which the corresponding separator portion passes, as shown in Figs. 6 and 7.

Suitable means for reciprocating said separator 30 are provided, comprising a pair of arms 32, which are secured on a rock-shaft 34 mounted in the frame, said shaft being rocked by means of an eccentric on shaft 8 operating through a connecting rod 36 and an arm 38 mounted on the shaft 34, so that each time the shaft 8 makes one complete revolution the separator plate 25 will be caused to make one complete reciprocation.

The table 25 is provided with a guideway 26 directly in front of the lift-holder 27, and at the front end of said lift-supporting faces 25', said guideway extends perpendicularly to the path of the carrier or holders 4, and a series of flat, lift-supporting and assembling plates 42 are arranged therein in superimposed position, and are longitudinally slidable in said guideway on each other. Said plates 42 are all of similar construction, but are varied according to conditions, the bottom plate extending the entire length of the groove 26 and the plates thereabove being successively shorter by the width of the lift engaging-portions of the separator 30. The front end of each plate 42, or the end next the carrier, is provided with a recess 42', which is shaped to receive a heel lift, the inner end of said recess being rounded to correspond to the rear end of the lift and the sides being extended in parallelism to the front end of the plate, from the widest part of the recess, the depth of the recess being such that, when the lift, which it is adapted to receive, is placed therein, its breast edge will be flush with the end of the plate.

Each plate 42, except the uppermost, is formed to provide a lift-supporting face 42'', on its upper side, directly in the rear of its lift-receiving recess 42', and the relative lengths of said plates is such, that, when they are all drawn back so that their rear ends engage an abutment 45 at the rear end of the groove 26, the supporting face

42" of each plate will be directly beneath the recess 42' of the next plate above it. Each plate is of a thickness approximately the same, or slightly greater than the thickness of the lifts, so that the upper surface of a lift resting on the face 42" of one plate within the recess 42' of the next above it, will be practically flush with the upper surface of the latter plate, but will not extend above it.

It may be here noted that the apparatus, described herein, is especially adapted for use in building heels made of leather pulp, which is formed in sheets made of a standard, uniform thickness, so that the lifts cut therefrom do not vary in thickness to any appreciable extent, and the plates 42 may be made to correspond in thickness almost exactly to the thickness of the lifts, although they may be, and preferably are, of slightly greater thickness, but the total of such excess thickness must not exceed the thickness of a single lift in the particular heel which is being built.

Each plate 42, except the uppermost, is further provided with a pair of longitudinally extending slots 43 which extend for a predetermined distance, as hereinafter explained, and each plate, except the bottom plate, is also provided with depending pins 44 which are adapted to extend into the slots 43 of the plate directly beneath it. Said slots 43 and pins 44 are so arranged that the pins of one plate will engage the rear ends of the slots in the plate next below it when their relative positions are such that the front end of the one plate is slightly in the rear of the recess 42' of the other. The arrangement is also such that each pin will engage the rear end of its slot, when all the plates are in engagement with the abutment 45. Said slots are terminated at their front ends in such a position that, when said plates 42 are moved forwardly, one on the other, their relative movement will be limited at positions in which the recessed ends thereof will be held in heel-forming relation, as shown in Fig. 9.

The plates 42 are designed to be made up in sets and to be readily removable from the guideway in which they are placed, so that one set may be substituted for another for heels of different shape.

The parts for actuating the separator 30 are so arranged that the operative or forward movement thereof carries its front end to such a point, before it is retracted, that the bottoms of its recesses 30' are in register with the adjacent side edges of the lift-receiving recesses 42', said plates 42 being then all in their retracted position, so that, when the separator is operated, the lifts which are removed from the bottoms of the stacks, will be pushed forwardly directly over, or into the recesses 42', whereby a

lift may be delivered into each of said recesses, simultaneously, each being supported on one of the faces 42", as indicated in dotted lines in Fig. 6.

To prevent the lifts from being pushed beyond said recesses 42', and to provide means to assist in moving the lifts into exact register therewith, so that they will fall therein, a stop plate 46, illustrated in detail in Figs. 3 and 4, is provided, which is shaped similarly to the transverse shape of the separator 30, being adapted to rest on the outer side end portions of the plates 42 and having recesses in its inner side which register with the outer edges of the recesses 42'. That is, when the plates 42 are in retracted position, as shown in Fig. 6, with the stop plate 46 in position thereon, as shown in Fig. 14, if the separator 30 is moved to its advanced position, the recesses 42' will be enclosed on both sides by the separator and stop plate.

With this arrangement, therefore, when the separator is advanced and engages the bottom lifts of the stacks and pushes them sidewise onto the plates 42, so that they should fall into the recesses 42', if a lift should happen to be misplaced or not moved into exact register with a recess and would otherwise be pushed beyond it, it will be pushed against said abutment, which will prevent such an occurrence and will assist in pushing the lift into position, so that it will be held in register with, and may fall into the recess intended to receive it. The plate 46 thus serves as an abutment for the lifts, and as a lift-adjusting or straightening device. Said stop plate 46 is mounted on arms 48 which project at right angles therewith at its ends and are connected by pivots 49 to ears 50 on the table 25, so that said plate may be swung upward out of engagement with the plates 42.

A pair of parallel guide rods 51 are mounted in front of the table 25 and extend horizontally in a direction parallel to the guideway 26 therein and an arm 52 is slidably mounted on said rods and is rigidly connected to the uppermost plate 42, and is provided with a handle 53 which projects vertically therefrom.

An inclined projection 54 is mounted on the arm 52 in position to pass beneath and engage the under side of the stop plate 46 so as to lift the same from in front of the ends of the plates 42, when the plates are advanced towards the carrier.

Before the heel-lifts are assembled in heel form, it is necessary to apply a coating of an adhesive to the surfaces of the said lifts, and, for this purpose, a frame 55 is provided, which is mounted to move vertically, directly over the plates 42, on a pair of rods 56 arranged at each end of the lift holder 27, said frame having a series of liquid-ce-

ment-holding tubes 57 rigidly secured there-to and vertically arranged side by side. Each tube 57 is closed at its lower end by an absorbent pad 58, preferably of felt or similar material, which is adapted to be-
5 come saturated with the cement placed in the tube, but which will retain the cement therein. The cross sectional shape of each tube, and its corresponding pad is made to
10 correspond to the shape of the heel lift which is to be placed in the compartment 28 directly in the rear thereof, and is also ar-
ranged directly over the recesses 42' of the corresponding plate 42 when in the initial
15 position of Fig. 6, so that, when the frame 55 is lowered, the pad 58 of each tube will register exactly with a recess 42', or will be brought into engagement with the lift held therein throughout practically its en-
20 tire surface. A hand-lever 60 is pivotally mounted at 61 at the rear end of the table 25, and is loosely connected to the frame 55 by a pivot 62, so that, when the lever 60 is de-
25 pressed, the frame 55 will be pushed downwardly on the guide rods 56. A pair of springs 64 are connected to the lift holder 27 and to the frame 55 as indicated on
30 Figs. 1 and 5 and act normally to support the frame in the raised position of Figs. 1 and 5.

A pair of fingers 65 are slidably mounted in lugs 66 on each side of each tube 57, so that each finger extends in close proximity to the pad at its opposite sides, and springs
35 67 are arranged on said shank-portions of said fingers between the uppermost of said lug 67 and a stop-collar 68 thereon, said collar 68 being arranged to engage the lower-
40 most lugs 66 and to limit the downward movement of the fingers 65 at such point that the end portions thereof will normally project slightly beyond the bottom surface of
45 the pad 58, as indicated in Fig. 5.

The operation of this portion of the de-
vice is as follows:—

Each tube 57 which is to be used for cementing purposes, is supplied with liquid-cement, and, after the separator 30 has been operated to deliver a set of lifts to the recesses 42', as already described, and illus-
50 trated in dotted lines in Fig. 6, the hand-
lever 60 is depressed, causing the pads 58 to be pressed down against the lifts directly therebeneath, as indicated in Fig. 10, apply-
55 ing a coating of cement to the practically entire upper surface thereof. That is, the pads are preferably slightly smaller in size, so that a small portion closely adjacent the edge, may not be coated, but whether such portion is, or is not coated is immaterial.

Inasmuch as the lifts must fit quite closely in the recesses 42', it will frequently happen that, while the lifts may be delivered prac-
60 tically in exact register with said recesses, they will not fall down therein, so that they

rest firmly on the upper sides of the plates, directly beneath, on the faces 42''. As the pads 58 are pressed firmly against said lifts, in applying the cement thereto, they will, at the same time, act to force the lifts down into said recesses, in case they are not already in this position, thus performing two different functions at one operation.

The pads 58, being saturated with an ad-
hesive, have a tendency to adhere to the sur-
75 face of the lifts and thus tend to raise the lifts from the recesses when they are lifted, upon release of the handle, but this is prevented by the fingers, the ends of which are ar-
ranged to engage the lifts before they are
80 engaged by the pads, so that, on the reverse motion, the separation from the lifts will be in the reverse order, that is, each lift will be held down firmly in its recess by the rods 65 until the pad 58 which has been pressed
85 thereagainst, has been raised out of contact therewith.

The lifts having been delivered to the re-
cesses 42' of the sliding plates 42, and a coat-
90 ing of cement having been applied to the upper surfaces of said lifts, the operation of the plates 42 in collecting them in heel form is as follows:—

The operator pulls the handle 53 toward the carrier causing the uppermost plate 42 to
95 be moved forwardly in the groove 26. This movement forces the wedge 54 beneath the stop-plate 46, and causes the same to be swung upwardly so that it will not obstruct the forward movement thereof, as shown in
100 Fig. 17. As the plate is moved along on the plate next below it, it pushes the lift contained in its recess 42' along on the face 42'' of said plate next beneath it, and causes the same to be slid onto the next lift which is held in the recess of said next plate, this movement continuing until the uppermost lift is carried slightly beyond, or in heel-
105 forming relation with the lift next below it, at which time the pins 44, or the upper-
110 most plate will engage the front ends of the slots 43 in said plate next below it, causing the latter plate to be moved forward in like manner. As the handle 53 is moved towards the carrier, this operation is continued, each successive plate first moving the lift which it engages forwardly on the plate next beneath it, and onto the next succeeding lift, as indicated in Fig. 8, so that the lifts are
115 collected in a pile and at the end of this movement will be held in heel-form on the bottom of the table. The guideway 26 is so arranged that the lowermost of the plates 42 is movable onto the carrier, exactly at the level thereof, so that, on further movement of said plates, they will carry the assembled lifts onto the holder 4, which is in position in front thereof, and will press the same against the breast-engaging abutment 11 of the holder, the lifts being held firmly in heel
120 125 130 135

form between said sliding plates and the abutment 11, as indicated in Fig. 9.

When the handle 53 is pushed back from the extreme forward position, to which it may be moved, as described, each slide will be moved back on the one next below it, until the pins 44 of each plate engage the rear ends of the slots 43 of the plate beneath it, and the "lost motion" permitted by said 10 slots, is all taken up and all the slides engage the abutment 45 at their rear ends.

A finger 70 is rigidly connected to the arm 52 and extends downwardly and then horizontally therefrom, and the extreme 15 end thereof is arranged in position to engage the lower end of the dog 18, when the plates 42 have been advanced to their extreme forward position, so that the lifts are pressed into heel form against the 20 breast gage 11, as shown in Fig. 9, causing said dog to become disengaged from the vertically movable support 17, so that the spring 13, which is much stronger than the spring 20, will be free to overcome said 25 spring 20 and to press the lift-clamping-plate 10 onto the pile of lifts which have been delivered to its holder, so as to press the cemented lifts together. The clamping plate 10 may be released just before the 30 lifts are pressed against the breast gage 11, as the lifts may be slid into final position while they are clamped by the plate 10.

While the treadle 9 may be depressed by the operator to start the machine, so that 35 the carrier will be moved the distance between two holders, in order that the operation may be facilitated, and to avoid the possibility that one or more of the assembled plates may not be withdrawn from the 40 holder when the carrier is started, with the consequent result that the heel would probably be displaced, or damage done, by reason of the engagement of the clamped heel with such plates as have not been withdrawn, when the heel is moved along with the carrier, and, further, to insure the complete withdrawal of the plates into position to receive the lifts from beneath the stacks, when the carrier is started and the lift separator 45 is operated, I provide means whereby the normally inoperative driving mechanism, which may be caused to operate by depressing the treadle, may be automatically operated at the end of the return movement 50 of the assembling plates.

An embodiment of means whereby this result may be accomplished is illustrated in Figs. 1, 5, 13, 18, and 19, in which a link 60 71 is connected at one end to the clutch operating lever 72, and at the opposite end to one arm of a bell-crank lever 73, shown in detail in Fig. 19, mounted to swing horizontally on the machine frame, as shown in Fig. 1, the opposite arm of the lever 73 being connected, by a link 75, to one end of

a lever 76, which is pivoted, at the opposite end, on the supporting post 77, as shown in detail in Fig. 18, and so arranged that, just before the handle 53 is withdrawn to its extreme limit, as shown in Fig. 5, the depending portion of the finger 70 will engage an intermediate portion thereof, as shown in Fig. 18, and, acting through said link 75, lever 73, and link 71, cause a pull on the lever 72, so that the clutch mechanism will 70 be operated and the machine started. The clutch mechanism which is employed is, preferably, of the well-known type which necessitates the release of its operating lever before it can again be operated to start the 75 machine.

The operation of the machine, as a whole, is as follows:—

When the carrier-driving-mechanism is 80 operated, so that each holder is moved a distance equal to its length, the separator 30 will be operated, and will deliver a series of lifts to the lift-assembling plates 42. The operator then presses down on the hand-lever 60, so as to apply a coating of cement 85 to the upper surfaces of the lifts, which have thus been delivered, at the same time pressing the lifts down into the recesses 42', as already described. He then moves the handle 53 towards the carrier, and, as the plates 42 are moved one on the other, the lifts are collected in heel form and delivered to the holder, which is directly in front of them, the collected lifts being automatically 90 clamped thereon, in heel form, at the end 95 of the assembling operation, as shown in Fig. 13.

The plates 42 are then moved back to 100 their initial positions, and, just before the finger 70 reaches its extreme withdrawn position, it engages the lever 76 and operates the clutch-mechanism, so that the carrier moves forward to the next position. The roll 14, of the particular holder which has 105 just clamped the heel, will, at the same time, be moved out of contact with the rib section 16, and into contact with the supplemental lift-pressing-mechanism, described in my application, Serial No. 849,835, so that the heel is placed under pressure additional to 110 that applied through the spring 13. As soon as the roll 14 is moved out of contact with the rib section 16, the spring 20 will be free to return said section to its normal position, 115 where it will be again locked by the dog 18, as shown in Fig. 5, and will support the lift-clamping mechanism of the next holder, as the roll of such mechanism passes onto the same. During this movement of the carrier, an additional set of lifts will be 120 delivered to the lift-assembling plates, and the operation will then be repeated.

The cementing, assembling, and clamping operations may thus be continuously performed. 125 130

I claim:—

1. In a heel-making machine, a series of superimposed lift-assembling plates, each plate having a lift-receiving recess in its front end, and a lift supporting face in the rear thereof, so arranged that a lift supported on the face of one plate will be held in the recess of the next above it, and said plates being forwardly movable to bring the recesses of the different plates into approximate register. 65
2. In a heel-making machine, a series of superimposed lift-assembling plates each having a lift-supporting face on its upper side and a lift-receiving recess in its front end, means permitting relative forward movement of said plates, and stops for limiting the movement of adjacent plates at points where the recess of each plate is in approximate register with that of the next adjacent plate, but varying therefrom according to the variations of the desired relative positions of the lifts when in heel form. 70
3. In a heel-making machine, a heel form composed of a series of forming members corresponding in number to the lifts of the heel to be formed and constructed to be held in forming relation, one over the other, and means permitting relative movement of said members longitudinally of the heel, said members having lift-supporting portions adjacent their forming portions and being movable from positions in which said portions are in lift-receiving position, to collect the lifts in heel form. 75
4. In a heel-making machine, a series of superimposed lift-assembling plates having their front edge-portions recessed to receive the rounded end-portions of corresponding lifts of a heel and having lift-supporting faces in the rear thereof, said plates being so held that the sides of the recess of one plate enclose the face of the one beneath it and being forwardly movable to slide the lift held on one face onto the lift held in the recess of the next plate therebeneath, and means to arrest the forward movement of said plates in position to cause the several recesses thereof to hold the lifts in heel form. 80
5. In a heel-making machine, a series of superimposed lift-assembling plates having their front edge-portions recessed to receive the rounded end-portions of corresponding lifts of a heel and having lift-supporting faces in the rear thereof, said plates being so held that the sides of the recess of one plate enclose the face of the one beneath it, and being forwardly movable to slide the lift held on one face onto the lift held in the recess of the next plate therebeneath, and a stationary breast gage at the end of the collecting movement of plates disposed to engage the breast edge of the lifts and limit the forward movement thereof. 85
6. In a heel-making machine, a series of superimposed lift-assembling plates, each plate having a lift-receiving recess in its front end and a lift-supporting face directly in the rear of said recess, to support a lift in the recess of the plate next above, and being limited to slide over the plate next beneath it, between a position in which its recessed end is directly in the rear of the supporting face of such plate to a position in which its recessed end is in heel-forming register with the recessed end thereof. 90
7. In a heel-making machine, a series of superimposed lift-assembling plates, each plate having a lift-engaging front end and a lift-supporting face directly in the rear thereof, and being limited to slide over the plate next beneath, between a position in which its lift-engaging end is directly in the rear of the supporting face of such plate and a position in which its said end is in heel-forming relation with the lift-engaging end of the plate therebeneath, to collect the lifts in heel form as said plates are moved to their extreme forward positions. 95
8. In a heel-making machine, a series of superimposed lift-assembling plates, each plate having a lift-engaging front end and a lift-supporting face directly in the rear thereof, and being arranged to slide over the plate next beneath, between a position in which its lift-engaging end is directly in the rear of the supporting face of such plate and a position in which its said end is in heel-forming relation with the lift-engaging end of the plate therebeneath, to collect the lifts in heel form as said plates are moved to their extreme forward positions, and a heel-forming abutment arranged to engage the opposite edges of said lifts, from that engaged by said engaging ends, at the end of the lift-collecting movement of said plates, to hold the lifts in heel form at opposite points. 100
9. In a heel-making machine, a series of superimposed lift-assembling plates, each plate having a lift-supporting face on its upper side, and a recessed front end formed to engage the rounded rear end of a lift, said plates being relatively movable one over the other, from a position, in which the recessed end of one plate embraces the face of the one directly beneath it, to a position in which said recessed end is in heel-forming relation with the recessed end of the latter, to collect the lifts, resting on the faces of said plates, in heel form. 105
10. In a heel-making machine, a series of superimposed lift-assembling plates, each plate having a lift-engaging front end and a lift-supporting face directly in the rear thereof, and being limited to slide over the 110
- 115
- 120
- 125

plate next beneath it, between a position in which its lift-engaging end is directly in the rear of the supporting face of such plate and a position in which its said end is in 65
8 heel-forming relation with the lift-engaging end of the plate therebeneath, to collect the lifts in heel form as said plates are moved to their extreme forward positions, and an abutment disposed in front of said plates 70
10 in position to be engaged by the breast edges of the lifts at the end of said collecting movement.

11. In a heel-making machine, a row of supports for holding a series of cemented 15 heel lifts in correspondingly disposed positions, a series of heel-holders successively movable into a lift-receiving position at one end of said row of supports, and means to collect said lifts and deliver them in a pile 80
20 onto each holder successively while in said position.

12. In a heel-making machine, a row of supports for holding a series of cemented heel lifts in correspondingly disposed positions, a series of heel-holders movable, successively into a position at one end of 85
25 said row, and means to collect said lifts and deliver them in a pile onto each holder while in said position.

13. In a heel-making machine, a row of supports for holding a series of cemented heel lifts in correspondingly disposed positions, a series of heel-holders successively movable into a lift-receiving position at one 90
30 end of said row of supports, means to collect said lifts and deliver them in a pile onto each holder, successively, while in said position, and a clamping device on each holder for clamping the lifts thereon when delivered thereto.

14. In a heel-making machine, a row of supports for holding a series of cemented heel lifts in correspondingly disposed positions, a series of heel-holders successively movable into a lift-receiving position at one 95
45 end of said row of supports, means to collect said lifts and deliver them in a pile onto each holder successively, a clamping device on each holder and automatic means for moving said device into clamping position 100
50 when the lifts are delivered onto the holder.

15. In a heel-making machine, a row of supports for holding a series of cemented heel lifts, a series of heel-holders successively movable to a heel-receiving position at the end of said row of supports, said 105
55 supports being movable in the direction of said row to collect the lifts thereon in a pile and deliver them to said holders, successively, when in said receiving position, and means on each holder for clamping the pile of lifts thereon.

16. In a heel-making machine, a heel-holder having a clamping device, a heel-

forming device movable to said heel-holder 65
to deliver an assembled heel thereto, and means automatically operated by said forming device as it delivers a heel to said holder to move said clamping-device to clamp the heel on the holder. 70

17. In a heel-making machine, a heel-holder, a heel-clamping device therefor, means normally actuated to move said clamping device to clamp an assembled heel on said holder, means to hold said clamping device out of clamping position, a heel-forming device movable to deliver an assembled heel to said holder, and means, operated by said heel-forming device as it delivers a heel to said holder, to release said 80
75 clamping device to permit its actuating means to clamp the heel on the holder.

18. In a heel-making machine, a series of heel-holders successively movable to a heel-receiving position, heel-clamping means for 85
each holder, heel-forming means movable to deliver an assembled heel to each holder when in said receiving position, and means, automatically operated by said forming means, as it delivers an assembled heel to 90
95 each holder, to operate said clamping means to clamp the heel thereon.

19. In a heel-making machine, a heel-holder, a heel-forming device movable to deliver an assembled heel to said holder, 95
a clamping device for said holder, having a spring for moving it into clamping position, means to compress said spring and hold each clamping device out of clamping position, and means, automatically operated 100
100 by said heel-forming means when it delivers the assembled lifts to said holder, to release said spring and permit it to move said clamping device to clamping position.

20. In a heel-making machine, a holder having a series of compartments each arranged to receive a stack of lifts and to support the bottom lifts thereof at different elevations, which vary successively by the thickness of the lifts, a correspondingly arranged series of lift-supports disposed adjacent thereto, a separating device movable to deliver the bottom lift of each stack onto the support corresponding thereto, and means to move said supports to move each 110
115 lift onto the next successively, and collect them in a pile.

21. In a heel-making machine, a lift-holder having a row of vertically disposed compartments each adapted to hold a stack of lifts therein, a row of lift-supports at one side of said compartments corresponding in number thereto and arranged in approximately parallel relation to the line thereof, separating devices movable transversely of said line to deliver a lift from each of said stacks to the support corresponding thereto, and means to move said 120
125

supports in the line thereof, to collect the lifts held thereon in a pile.

22. In a heel-making machine, a series of lift-supports arranged in a row to support a series of lifts thereon with their upper surfaces exposed, means to apply cement simultaneously to said upper surfaces of said lifts, and means movable in the direction of said row to collect said lifts in a pile.

23. In a heel-making machine, a series of lift-supports horizontally disposed in a row at elevations which are successively lower, by the thickness of the lifts, from one end 15 of the row to the other, a series of cementing devices having cement-applying faces at correspondingly different elevations, and movable to apply cement simultaneously to the upper surfaces of the lifts while held by 20 said supports, and means to move said lifts one over the other to collect them in a pile.

24. In a heel-making machine, a holder having a series of compartments each arranged to receive a stack of lifts, a corresponding series of lift-supports arranged adjacent thereto, a separating device movable to deliver a lift from each stack simultaneously onto the support corresponding thereto, means to apply cement simultaneously to 30 said lifts while held on said supports, and means to collect the cemented lifts held on said supports in a pile.

25. In a heel-making machine a holder having a series of compartments each arranged to receive a stack of lifts, a corresponding series of lift supports arranged adjacent thereto, a separating device movable to deliver a lift from the bottom of each stack onto the support corresponding 40 thereto, so that the upper surface of each lift is exposed, means to apply cement to said upper surfaces of said lifts while held on said supports, and means to collect the cemented lifts, held on said supports, in a pile.

26. In a heel-making machine, a lift-holder having a row of vertically disposed compartments each adapted to hold a stack of lifts therein, a row of lift-supports, at one 50 side of said compartments, corresponding in number thereto and horizontally arranged at elevations which are successively lower by approximately the thickness of the lifts, separating devices movable to deliver a lift from each of said stacks to the support corresponding thereto, and means to move said supports in the line of their arrangement to collect said lifts in a pile.

27. In a heel-making machine, a lift-holder having a series of vertically disposed compartments arranged in a row, each to receive a stack of lifts therein, supporting means at the bottom of each stack arranged at elevations which increase from one end 65 of the row according to the approximate

thickness of the lifts, a corresponding series of lift-supports at one side of said stacks disposed at corresponding elevations, and separating means for each stack movable horizontally at corresponding elevations to 70 remove the bottom lifts from said stacks and deliver them to said supports.

28. In a heel-making machine, a row of vertically disposed compartments each adapted to hold a stack of lifts therein a lift-assembling device having a row of lift-receiving recesses disposed at one side of said compartments and arranged to hold the lifts in corresponding positions, separating means to deliver a lift from the bottom of each stack into register with said recesses, a vertically movable lift-engaging device arranged to engage the lifts simultaneously and press them into said recesses and means to operate said lift-assembling device to collect the lifts in said recesses in a pile.

29. In a heel-making machine, a row of vertically disposed compartments each adapted to hold a stack of lifts therein, a lift-assembling device having a row of lift-receiving recesses disposed at one side of said compartments and arranged to hold the lifts in corresponding positions, separating means to deliver a lift from the bottom of each stack into register with said recesses, and a series of cementing pads vertically movable to press said lifts into said recesses 85 and to apply cement to the upper surfaces thereof.

30. In a heel-making machine, a row of vertically disposed compartments each adapted to hold a stack of lifts therein, a lift-assembling device having a row of lift-receiving recesses disposed at one side of said compartments and arranged to hold the lifts in corresponding positions, separating means to deliver a lift from the bottom of each stack into register with said recesses, and means at the opposite sides of said recesses from said separating-means to obstruct the movement of the lifts beyond said recesses by said separating means.

31. In a heel-making machine, a row of compartments each adapted to hold a stack of lifts therein, a lift-assembling device having a corresponding row of lift-receiving supports, lift-separating devices movable transversely of said row to deliver a lift from each stack to said supports and means at the opposite side of said supports from said separating devices to limit the movement of the lifts by said separating devices.

32. In a heel-making machine, a row of compartments each adapted to hold a stack of lifts therein, a lift-assembling device comprising a series of lift-supporting plates having supporting faces held at different elevations, and movable to assemble the lifts on said faces, a lift-delivering device movable transversely of said row from one side

- thereof to slide the lifts onto said faces, and a stop device at the opposite side of said row arranged to prevent movement of the lifts beyond said faces and supported to permit 5 upward movement out of the paths of said plates during the assembling movement thereof.
33. In a heel-making machine, a carrier comprising a series of heel holders having 10 means for clamping a heel thereon, means to actuate said carrier to move said holders successively into a heel-receiving position, and a lift-assembling device movable to deliver the assembled lifts onto each holder 15 when in said receiving position.
34. In a heel-making machine, a carrier comprising a series of heel-holders having means for clamping a heel thereon, means to actuate said carrier to move said holders successively into a heel-receiving position, lift-supporting means for holding a series of lifts in corresponding positions, means to apply cement to the lifts while held in 20 said positions, and means to collect the cemented lifts in heel form and to deliver them to said holders, successively, while held in said receiving position.
35. In a heel-making machine, a row of supports for holding a row of heel-lifts 25 with one side uppermost, a corresponding row of cement-applying devices, means to operate said cementing devices to apply cement to the uppermost sides of the lifts while held in said supports and means to collect the cemented lifts in a pile.
36. In a heel-making machine, a row of lift-receiving compartments, a row of supports at one side thereof, means to deliver a lift from each compartment to each of said 40 supports with one side uppermost, means to apply cement to the uppermost sides of the lifts while held by said supports, and means to collect the cemented lifts in a pile.
37. In a heel-making machine, a row of supports, for holding a series of heel-lifts 45 with one side uppermost, a corresponding row of cement-receiving tubes having depending lower ends, an absorbent pad for closing the lower end of each tube, means to move said tubes to bring said pads in contact with the uppermost faces of the lifts held on said supports and means to collect the cemented lifts in a pile.
38. In a heel-making machine, a carrier 50 comprising a series of heel-holders successively movable to a heel-receiving position, a row of lift-receiving compartments, and a corresponding row of lift supports arranged side by side, said row of lift supports terminating at one end adjacent the receiving 55 position of said carrier, means to deliver a lift from each of said compartments to said supports, means to apply cement to the lifts while held by said supports, and means, movable in the line of said supports,

to collect the lifts therefrom, and deliver them in assembled form to one of said holders while in said receiving position.

39. In a heel-making machine, a carrier comprising a series of heel-holders, means 70 to drive said carrier to bring said holders successively into a heel-receiving position, a heel-clamping plate on each holder movable to and from positions to clamp a heel thereon, and spring actuated to move to a 75 clamping position, means to move each clamping-plate out of clamping position as the holder moves towards said receiving position, to release the heel clamped thereby, a movable support to hold each clamp- 80 ing-plate out of clamping position while its holder is in receiving position, means to deliver a heel to each holder while in receiving position and means to release said support to permit the clamping-plate supported thereby, to be moved to clamping position while the heel is held in assembled position on the holder.

40. In a heel-making machine, a series of heel-holders, each holder having means for 90 clamping a heel thereon, means to move said holders successively into a heel-receiving position, and a heel-forming device movable to deliver the assembled lifts onto each holder when in said receiving position. 95

41. In a heel-making machine, a series of heel-holders, each holder having means for clamping a heel thereon, means to move said holders successively into a heel-receiving position, and a heel-forming device reciprocally movable to and from said position to deliver the assembled lifts to said holders, successively, when in said position. 100

42. In a heel-making machine, a series of heel-holders, each holder having a heel-receiving seat and means for clamping a heel thereon, means to move said holders in a predetermined path, successively into a heel-receiving position in which the seat thereof is held horizontally, and a heel-forming device movable transversely of said path to deliver the assembled lifts onto each holder when in said receiving position. 110

43. In a heel-making machine, a series of heel-holders, each holder having a heel-receiving seat and means for clamping a heel thereon, means to move said holders in a predetermined path, into a heel-receiving position, successively, in which the seat thereof is held horizontally, and a heel-forming device horizontally reciprocal transversely of said path to deliver assembled lifts onto each holder when in said receiving position. 115

44. In a heel-making machine, a series of heel-holders, each holder having a heel-receiving seat and a heel-breast engaging abutment at one side of said seat, means to move said holders in a predetermined path into a heel-receiving position, successively, a heel- 120

forming member adapted to conform to the rear end of a heel and reciprocally movable transversely of said path towards and from the abutment of each holder, when in said receiving position, to deliver a pile of heel lifts assembled therein onto the seat of the holder and hold them against its abutment in heel form, and means on each holder to clamp the heel on its seat while thus held and thereafter to permit said forming member to be moved out of engagement with the heel.

45. In a heel-making machine, a series of heel-holders, successively movable into a lift-receiving position, heel-forming means movable to deliver the assembled lifts onto said holders when in said position, a clamping device for each holder, and automatic means for moving each clamping device into clamping position when the assembled lifts are delivered onto its corresponding holder.

46. In a heel-making machine, a heel-holder having a heel-receiving face, a clamping device, spring actuated to clamp a heel on said face, a trip device for holding said clamping device in an inoperative position, and a heel-forming member movable to deliver the assembled lifts onto said face, and to operate said trip device to permit the spring of said clamping device to clamp the lifts when in position on said face.

47. In a heel-making machine, a series of heel-holders successively movable into a lift-receiving position, a clamping device mounted on each holder spring actuated to clamp a heel on its corresponding holder, supporting means to hold each clamping device in an inoperative position when its holder is in said receiving position, heel-forming means movable to deliver a pile of lifts, in heel form, onto each holder, when in said position, and means, automatically operated by said forming means, as it delivers the lifts onto a holder, to release the actuating spring of its corresponding clamping device to clamp the lifts thereon.

48. In a heel-making machine, a carrier comprising a series of heel holders, movable successively into a heel-receiving position, normally inoperative driving-means therefor, controlling-means to cause operation of said driving-means to move one holder from said position and the next holder into said position, a heel-forming member supported independently of said carrier and movable to deliver an assembled heel to said holders when in receiving position, a clamping device for each holder, means to move said clamping device to clamp a heel thereon when delivered thereto by said member, and means actuated by said member as it is withdrawn from the holder, to operate said controlling-means.

49. In a heel-making machine, a carrier comprising a series of heel holders, movable

successively into a heel-receiving position, normally inoperative driving-means therefor, controlling-means to cause operation of said driving-means to move one holder from said position and the next holder into said position, a heel-forming member on each holder, a cooperating heel-forming member supported independently of the carrier and movable into forming relation with the member of each holder when in said position, a clamping device for each holder, means to move each clamping device to clamp a heel on its holder when held thereon between said members and means, actuated by said cooperating member, when it is moved out of forming relation, to operate said controlling-means.

50. In a heel-making machine, a carrier comprising a series of heel holders, movable successively into a heel-receiving position, normally inoperative driving-means therefor, controlling-means to cause operation of said driving-means to move one holder from said position and the next holder into said position, a heel-forming member supported independently of the carrier and movable into position to hold the lifts in heel form over each holder when in said position, a clamping device for each holder and means actuated by said heel-forming member when it is moved into position over a holder, to operate the clamping device thereof to clamp a heel thereon, and when withdrawn therefrom, to operate said controlling means.

51. In a heel-making machine, a carrier comprising a series of heel holders, movable successively into a heel-receiving position, normally inoperative driving-means therefor, controlling-means to cause operation of said driving-means to move one holder from said position and the next holder into said position, a heel-forming member reciprocally movable to and from said position to deliver assembled heels to said holders successively, a clamping device for each holder, means, actuated by said member at the end of its delivering movement to a holder in said position, to operate the clamping device thereof and means actuated by said member at the end of its return movement, to operate said controlling-means.

52. A heel-building machine having, in combination, a series of intermittently and bodily movable heel block presses, a former arranged and adapted to shape piled heel lifts into the proper contour of block, and means for actuating the former to transfer the heel blocks to the presses.

53. A heel-building machine having, in combination, a series of automatically opening and closing presses for receiving and holding blocks under pressure, and means for shaping piled, pasted heel lifts into heel blocks, said shaping means being movable to transfer the blocks to said presses, hold

the blocks thereat until the presses close, and then be withdrawn leaving the blocks in the presses.

54. A heel-building machine having, in combination, an endless series of heel block presses operative to clamp and carry green heel blocks for a period sufficient to permit substantial setting of the paste, and then automatically release the blocks, means for shaping freshly pasted lifts into heel blocks of given form, and means to operate said shaping means to transfer the blocks to the presses, said shaping means being constructed to permit withdrawal from the blocks when they are clamped by the presses.

55. A heel-building machine having, in combination, a series of heel block presses intermittently movable through a predetermined orbit, means for automatically opening and closing the presses at predetermined stations in their orbit to permit the insertion and discharge of heel blocks, and means for shaping freshly pasted heel lifts into heel blocks of predetermined contour, operative to transfer the shaped block to an open press and deposit it therein.

56. A heel-building machine having, in combination, an intermittently movable endless series of heel-block presses, a former in which a heel-block may be assembled, and means for moving the former to bring the block assembled therein into position within one of the preses during a dwell in the intermittent movement of the latter.

57. A heel-building machine, having, in combination, a heel block press comprising a series of bed plates successively movable to heel receiving position and a press platen movable toward and from each bed plate; a former, constructed to receive lifts in a pile with their breast edges alined, movable to successively load said bed plates, while in heel receiving position, with assembled heels; and means for automatically operating said press platens as the heels are delivered to the bed plates by the former.

58. In a heel-making machine, a series of heel-clamps each comprising a spring-actuated member and a base member, means to move said clamps in a predetermined path, successively, into a heel-receiving position, a heel-form open at top and bottom, and movable between a lift-assembling position at one side of the path of movement of said clamps and said heel-receiving position, to deliver the assembled lifts between said members, and means to release the spring actuated member of each clamp when the form has delivered an assembled heel thereto.

In testimony whereof, I have signed my name to this specification in the presence of two subscribing witnesses.
